UNITED STATES PATENT OFFICE.

BENJAMIN F. TAYLOR, OF TARBORO, NORTH CAROLINA.

DESIGN FOR A BOTTLE.

Application filed October 10, 1927. Serial No. 23,698. Term of patent 14 years.

To all whom it may concern:

Be it known that I, BENJAMIN F. TAYLOR, a citizen of the United States, residing at St. Andrews St., city of Tarboro, in the county of Edgecombe and State of N. Carolina, have invented a new, original, and ornamental Design for Bottles, of which the following is a specification, reference being had to the accompanying drawing, forming part thereof. The figure is a side view in elevation of a bottle, showing my new design.

I claim:

The ornamental design for a bottle, as shown.

BENJAMIN F. TAYLOR.
